(57) CLAIM

The ornamental design for a package, as shown and described.

DESCRIPTION

The package can comprise a stand-up plastic bag with a window therein. The package may have a ZIPLOC® closure, or equivalent. The Package can be used to contain one or more water soluble pouches containing a detergent composition therein.

FIG. 1 is a perspective view of a package, embodying our new design;

FIG. 2 is a front view thereof;

FIG. 3 is a rear view thereof;

FIG. 4 is a side elevational view thereof;

FIG. 5 is a side elevational view from the other side thereof;

FIG. 6 is a bottom view thereof;

FIG. 7 is a top view thereof; and,

FIG. 8 is a front view of the package showing a pouch in the window of the package.

Any broken lines shown in the drawings are for illustrative purposes only and form no part of the claimed design.
